(57) **CLAIM**

The ornamental design for an insulation panel, as shown and described.

DESCRIPTION

FIG. 1 is a perspective view of a first embodiment of the insulation panel;

FIG. 2 is a top view of the FIG. 1 insulation panel, the bottom view being a mirror image thereof;

FIG. 3 is a left side view of the FIG. 1 insulation panel;

FIG. 4 is a front elevation view of the FIG. 1 insulation panel;

FIG. 5 is a right side view of the FIG. 1 insulation panel; FIG. 6 is a perspective view of a second embodiment of the insulation panel having a width that is greater than that of the first embodiment;

FIG. 7 is a perspective view of a third embodiment of the insulation panel having a width that is greater than that of the first and second embodiments; and,

FIG. 8 is a perspective view of a fourth embodiment of the insulation panel having a width that is greater than that of the first, second and third embodiments.

The drawings include symbolic break lines. The appearance of any portion of the insulation panel between the break lines forms no part of the claimed design.

The broken lines are shown for the purpose of illustrating parts of the insulation panel that form no part of the claim.
